(57) **CLAIM**

The ornamental design for a tire, as shown and described.

DESCRIPTION

FIG. 1 is a perspective view of the tire;

FIG. 2 is a front elevation view of the tire;

FIG. 3 is side plan view of the tire;

FIG. 4 is an enlarged fragmentary view of the tire shown in FIG. 2; and,

FIG. 5 is an enlarged perspective view of the tire.

In the drawings, the broken lines depict portions of the tire that form no part of the claimed design. All other broken lines in FIGS. 4 and 5 are for the purpose of depicting an enlarged view.

1 Claim, 5 Drawing Sheets
